UNITED STATES PATENT OFFICE.

GEORGE R. LUM, OF NEW YORK, N. Y., ASSIGNOR TO BELL TELEPHONE LABORATORIES, INCORPORATED, OF NEW YORK, N. Y., A CORPORATION OF NEW YORK.

DESIGN FOR A DIAPHRAGM FOR A LOUD SPEAKER.

Application filed November 30, 1927. Serial No. 24,347. Term of patent 7 years.

To all whom it may concern:

Be it known that I, GEORGE R. LUM, a citizen of the United States, residing at New York, in the county of New York and State of New York, have invented a new, original, and ornamental Design for a Diaphragm for a Loud Speaker, of which the following is a specification, reference being had to the accompanying drawing, forming a part thereof.

Fig. 1 is a front view and Fig. 2 is a side

view of a loud speaker having a diaphragm showing my new design, a portion only of the ornamentation being shown, it being understood that the balance is a mere repeat.

I claim:

The ornamental design for a diaphragm for a loud speaker as shown.

In witness whereof, I hereunto subscribe my name this 29 day of November, 1927.

GEORGE R. LUM.
